UNITED STATES PATENT OFFICE.

JOEL SWARTZ, OF GETTYSBURG, PENNSYLVANIA.

BOOK-RACK.

SPECIFICATION forming part of Letters Patent No. 298,039, dated May 6, 1884.

Application filed January 24, 1882. (Model.)

To all whom it may concern:

Be it known that I, JOEL SWARTZ, a citizen of the United States, and a resident of Gettysburg, in the county of Adams, in the State of Pennsylvania, have invented certain new and useful Improvements in Book-Racks, of which the following is a full, clear, and exact description, reference being had to the accompanying drawings, illustrating the same.

10 My invention relates to a portable device for use on a desk or table and the like in supporting and retaining a book, pamphlet, or other publication in an open condition for use, to save manual fatigue and inconvenience in 15 reading or consulting; and the invention consists in a book-rack composed of a base to receive the bottom edge of a book, an attached frame to support the back of the book, a self-locking hinged brace for the frame, to hold the 20 rack in position, and spring-fingers to abut against the book to hold it open and prevent its leaves or pages from accidental turning, all substantially as hereinafter set forth and claimed.

25 In the drawings hereinbefore referred to, in the several figures of which like parts are similarly designated, Figure 1 shows the rack in front elevation; Fig. 2, in side elevation; and Fig. 3 is a perspective view of my rack in use, 30 an open book being in position thereon.

In constructing my rack I provide a base, *c*, preferably of wood, flat on its bottom side, and curved, hollowed out, or concaved at *d* on its upper side or face. To the rear edge of this 35 base is affixed a rearwardly-inclined frame, *A*, preferably of wire, having two uprights or legs, *e e*, provided with portions *e' e'*, by which latter the frame is secured to the base. The upper ends of the legs are provided with eyes 40 *e' e'*, connected by a cross-piece between them, the whole frame being most conveniently formed of a single piece of wire bent to shape and constituting the back of the rack.

The base and frame are held upright and 45 the book thereon supported against toppling over by a brace, *b*, hinged by loops *b' b'* in the eyes *e' e'* of the frame, outside the legs of said frame, and adapted to be swung out between the legs, as in Fig. 2, for use, and to be laid 50 up against the frame and base when not in use.

This brace is preferably V-shaped in outline, and the upper ends of its arms, which are

elastic or springy, are crooked or bent at *g h*, and the eyes of said arms have some play in the eyes of the back, so that when said brace 55 is swung back from the frame, as in Fig. 2, the resilience of the arm will cause the crooks *g h* to bind on the legs *e e*, and result in the locking or retention of the brace in its extended position, thus rendering it self-locking, preventing the accidental displacement of itself and the collapse or over-toppling of the rack. Pressure toward the base exerted upon the brace will restore it to its position for disuse.

To the front edge of the base is secured by 65 staples *m o n* a wire, *a*, which is bent vertically at *a' a'* outside its staples *m n*, and then bent again horizontally to form fingers *a' a'*, which overlie the base transversely, and which fingers preferably terminate in any suitable 70 armament, as eyes or loops *a' a'*. The wire *a* is drawn down into a curve by its center staple, *o*, whereby it is converted into a spring, the resilience of which will tend to throw its fingers down upon the base, as in Figs. 1 and 2. 75

When a book is to be placed upon the rack, the fingers can be lifted to admit it to the base-cavity *d*; but they will tend to press toward the book; hence when the book is opened to the page to be consulted, and at which place 80 it is desired to retain the book open, the fingers are released, and their armored ends, coming in contact with the book, will forcibly retain it open, the eyes, knobs, or loops *a' a'* on said fingers preventing the said fingers *a' a'* from defacing the book.

When the rack is to be used solely as a rest for a reader who will have to turn the leaves of his book often, the fingers may be turned down in front the base, and thus become inoperative for the time being.

This rack will also be found convenient for holding copy, reference-books, and other matter requiring frequent consultation. The angular bends *a' a'* in the spring fingers prevent 95 the disturbance of the stability of the rack under the operations of such fingers, it being understood that the stapled portion of the wire *a* forms a curved axis or shaft, with which said fingers turn as they are moved back and 100 forth over the base.

What I claim is—

1. In a book-rack having a base and back, a spring-brace swinging between the legs of

the back, and having end crooks, *g h*, loosely hinged to the back by loops *b' b'* engaging eyes outside the legs of said back, whereby it is adapted to be sprung in between the legs of 5 the back to lock it (the said brace) in position for use in sustaining the rack, substantially as described.

2. The combination, with the base, of the back provided with eyes projecting outside its 10 legs, and the brace hinged in said eyes swung between the legs of the back, and provided with the bends or crooks *g h* below the hinging-points, whereby it is adapted to be sprung in between the uprights of said back when 15 swung back from said eyes, to thereby lock it self in position, substantially as described.

3. A book-rack composed of a supporting-base, a back having eyes outside of its legs, a brace hinged between said legs to said back 20 by loops *b' b'* engaging its eyes, and having crooked or bent ends, substantially as described, so as to be sprung through the uprights thereof, and thereby be self-locking and

adjustable, and spring-fingers made in one piece and moving with a curved shaft, substantially as shown and described.

4. In a book-rack having a support for the back and lower edge of a book, the wire *a*, secured to the support in a curved line, substantially as set forth, by staples *m o n*, to convert 30 it into a spring, and having its ends bent to project over such support for holding the book in place thereon, all as and for the purpose described.

5. The wire *a*, curved as shown, and having 35 the bends *a' a'* and fingers *a² a²*, combined with a book-support, and means to secure the wire in its curved form thereto, whereby the fingers of said wire are retained in position to hold an open or other book in place upon the support, 40 and also retained in a reverse position to free the book, substantially as set forth.

JOEL SWARTZ.
